UNITED STATES PATENT OFFICE.

FREDERICK EAGON, OF CHICAGO, ILLINOIS, ASSIGNOR OF ONE-THIRD
TO HERMAN HOLZNAGEL, OF SAME PLACE.

CORNER-PIECE FOR BEDSTEADS.

SPECIFICATION forming part of Letters Patent No. 605,310, dated June 7, 1898.

Application filed April 5, 1897. Serial No. 630,899. (No model.)

To all whom it may concern:

Be it known that I, FREDERICK EAGON, a citizen of the United States, residing at the city of Chicago, in the county of Cook and State 5 of Illinois, have invented certain new and useful Improvements in Corner-Pieces for Bedsteads, of which the following is a description.

The object of my invention is to produce a corner clamp or fastening for iron bedsteads 10 to be used to connect the side and end pieces or springs of the bed to the corner-posts, which shall be cheap of manufacture, simple in construction, and efficient in use.

The clamp herein shown and described 15 forms the subject of a separate application for Letters Patent filed in Patent Office as Serial No. 648,735.

In the accompanying drawings, forming part of this specification, Figure 1 is a perspective view of the device, showing the springs connected to the corner. Fig. 2 is a perspective view of same device, the springs being omitted to show the hooked corner-iron. Fig. 3 is a view of the hooked corner-iron, 25 which slips and hooks into the clamp. Fig. 4 is a sectional view taken at the dotted line 4-4 of Fig. 2, and Fig. 5 a detached view of one side of the clamp.

A represents the corner-post of the bed, B 30 the side rail, and C the end or connecting rail, of an iron bedstead. The end rail may consist of a separate rail or it may consist of the springs directly connected to the corner, as shown in Fig. 1.

A clamp formed of two jaws or pieces D E, held together by a lock-nut and bolt connection F, is slid over or around the corner-post A, the bolt connection F of course allowing the parts D E to be separated, and when hugging the post A, the bolt connection being worked in proper direction, the parts D E come together and are tightly clamped onto the corner-post A. These clamp-pieces D E are peculiarly shaped, each having the half-round part a' to fit around the corner-post, part a having the flange a⁴ and the part a' extending over at the end to form a groove or channel a², closed at each end by a lug a³. (See Fig. 5.) The clamp-piece E ends in a flange a⁴, (see Fig. 4,) which fits in the channel a². This flange is kept from sliding up and

down and is held firmly in place by the lugs a³ at each end, thus keeping the clamp-pieces from moving over each other and keeping them in juxtaposition.

Each clamp-piece D E at the back end has the side flanges G and end pieces H, the two parts when put together forming a box shape or a housing, as shown in Fig. 4, into which the hook K and lug K' of the hooked corner-piece 60 L fit, the hook slipping over and resting on the connecting-bolt F, the lug K' assisting to keep the parts in steady and firm position. This corner-piece L consists of parts d d' at right angles, the part d' being cut away, as 65 shown, and broken midway by a flange plate or seat d², extending at right angles from the meeting edges between parts d d'. (See Fig. 3.) A hole d³ is placed in the seat d². Holes d⁴ are placed in the side flange G of each 70 clamp-piece D E, through which the connecting-bolt F passes.

When it is desired to use my device in the construction or use of an iron bed, the clamps or jaws D E are placed around the corner-post A and the connection-bolt F screwed up tightly. This pulls the jaws tightly together, and the curved parts a a' tightly impinge against the corner-post. The corner-piece L is then inserted in the space or housing created 80 by the flanges G and H, through which the connecting-bolt F passes, the hook K slipping over and resting on said bolt connection F. The side rails B and end rails or springs C are then connected together and to the corner-piece L by the bolt M, which securely holds them and the corner-pieces together. When in this position, the whole bed can be lifted 85 out of the clamps and slipped in again.

By the use of this device a bed-spring or a 90 rail can be connected to the corner of an iron bedstead or taken off at pleasure.

What I claim as new and of my invention, and desire to secure by Letters Patent, is—

1. In a corner-piece for bedsteads, a corner-piece formed like an angle-iron, having flanges d, d', seat d², lug K', hook K, in combination with a clamp composed of two jaws having flanges G, G, curved parts D, E; part D having a flange a⁴ and part E having channel a², 95 into which flange a⁴ of part D, fits, and interlocks and bolt connection F, the corner- 100

piece being detachably connected to the said clamp, as set forth.

2. In a corner-piece for iron bedsteads, an angle-iron L formed substantially as set forth and hook K, in combination with the sides and ends of the bedstead; and a clamp connected to the iron bed-post, the clamp being composed of the interlocking jaws D and E,

bolt F, the bolt F connecting the jaws D and E, the hook K on the corner-iron engaging 10 the bolt F, all combined and operating as set forth.

FREDERICK EAGON.
